Patented Aug. 17, 1920.

Inventor:
Charles Hofstetter,
By L. M. Heslop
Atty.

UNITED STATES PATENT OFFICE.

CHARLES HOFSTETTER, OF PEORIA, ILLINOIS.

VENTILATOR.

1,349,764.

Specification of Letters Patent. Patented Aug. 17, 1920.

Application filed October 4, 1918. Serial No. 256,892.

To all whom it may concern:

Be it known that I, CHARLES HOFSTETTER, citizen of the United States, residing at Peoria, in the county of Peoria and State of Illinois, have invented certain new and useful Improvements in Ventilators; and I do hereby declare that the following is a full, clear, and exact description of the invention, which will enable others skilled in the art to which it appertains to make and use the same.

This invention relates to improvements in ventilators, pertaining more particularly to ventilators for use on buildings.

One of the objects of the invention is the provision of a structure in which a perfect draft will be assured at all times, due to the large opening provided for the ventilating pipe. Also the provision of a structure that will prevent down drafts, and a valve or damper which in times of fire will be automatically released to close upon the said pipe.

Another object is the provision of a structure wherein there will be no places of lodgment upon which birds will be able to construct nests which would reduce the area of the outlet therefrom or obstruct the draft.

Still another object is the provision of a structure, parts of which can be readily removed on short notice in order to make repairs.

To the end that my invention may be understood, I have provided the accompanying drawing, showing the preferred embodiment of my invention, it being understood that slight changes may be made as may be suggested to the practical person.

Figure 1 shows my invention in elevation, parts being broken away to clearly illustrate the relation of the various elements one to another.

Fig. 2 is a plan of the same; and,

Fig. 3 shows certain parts, in perspective.

1 indicates the usual eduction pipe or flue communicating with the space to be ventilated. 2 is a skirt surrounding the same and extending at its ends above and below the open end of said pipe. Said skirt is spaced from the pipe or flue preferably flaring toward its upper end as shown to create a continuously increasing space around the said pipe.

3 indicates a series of vertically disposed braces, one of which is shown in perspective

in Fig. 3, which serve to secure the skirt to the pipe, said braces being spaced around the latter substantially as shown.

One edge of the brace is provided with a flange 4 to secure it to the pipe 1 by means of bolts 5, for example, while the other edge has the flange portions 6, Fig. 3, by which to secure it to the inner surface of the skirt 2 by means of bolts 7, for example.

8 indicates a series of braces, each of which is provided at one end with a flange 9 and at its opposite edge with a flange 10. These braces are secured by means of bolts 11, Figs. 1 and 3, to the upper end of the braces 3, being inclined at an angle to receive thereon a conically formed ring 12, secured by means of bolts or rivets 13 to the flanges 10.

Lying directly above the opening of the pipe or flue 1 and between it and the ring 12 is a cone-shaped cap 14 whose apex is substantially in line with the axis of said pipe or flue. This cap is supported in position by being secured to the flanges 9 of the braces 8 by means of bolts or rivets 15.

The said conical ring 12 is of such area and is so positioned that its upper edge extends over the outer edge of the cap while the lower edge of said ring extends down toward the skirt 2.

16 is a valve or damper which may be made in the form of two cones whose bases are secured together, the edge of the upper cone portion projecting beyond the lower one and adapted to lie upon the end of the pipe or flue, when in its closed position, as shown in broken lines.

17 is indicative of a pulley or other suitable portion suspended from the apex of the cap 14, and 18 is a chain attached at one end to the said valve or damper and extending up through the pulley and then down through the valve or damper and the flue 1, said valve or damper preferably having a tube 19 extending through it as a smooth guide for the said chain.

In practice the lower end of the chain may be attached to a fusible link of any well known type which in case of fire upon becoming fused will release the valve or damper and permit it to drop upon its seat upon said pipe or flue.

The distance from the top of the pipe 1 to the cap 14 is such that the valve or damper when raised to its highest point beneath said

cap will in no way reduce the area of the outlet of said pipe, the space between the pipe and the valve providing an area at least as great as that of the pipe 1.

5 The conical form of the lower part of the valve serves to deflect the air outwardly toward the skirt which is then drawn upward and outward between the ring 12 and the skirt as well as upward and outward in the 10 other direction between the said ring and the cap 14.

Preferably the said conical lower part extends nearly to the outer edge of the upper portion and thereby the ascending air passes 15 out in a clean sweep or without creating an eddy beneath the upper portion as would occur were this lower part of greatly less diameter. Furthermore, this construction serves to properly center the valve when 20 lowered upon the pipe, no other guide being necessary.

Preferably the braces 3 are recessed at 20, their vertical edges serving as guides for said valve or damper in its vertical movements.

25 As the normal position of the valve is its raised position as shown in continuous lines in Fig. 1, there are no surfaces upon which birds can build their nests the presence of 30 which would reduce the draft area.

The spaces between the several parts of the structure are at least equal to or greater in extent than the area of the pipe 1 so that 35 the draft is in no way interfered with under the most exacting conditions.

Strong winds striking the pipe 1 will be 40 deflected upwardly between the skirt and the pipe through the spaces between the braces passing out through the upper openings described and assist in creating a stronger upward draft through said pipe.

By extending the braces 3 downwardly for a short distance below the skirt they assist in deflecting the wind upward.

45 A convenient feature in my construction is that in case of repairs required inside the device the removal of the bolts 11 will permit the cap 14, the valve 16 and the ring 12 with its braces 8 to be removed bodily which 50 has been found to be of considerable advantage.

The area of the inlet at the bottom of the skirt of my device is at least equal to that of the pipe and at the upper end the area is 55 very much greater so that the air ascending between the skirt and pipe as well as that passing out of the eduction pipe itself is readily liberated, there being no choking. On the contrary the draft is increased because of the ease of passage of the air.

In addition, the cap 14 is but little greater in diameter than the pipe-opening so that 60 the air is not forced to move outward and downward beneath it as in older types, but 65 has an almost direct upward path of escape,

the said ring 12 being inserted to prevent down drafts.

Having thus described my invention, I claim:—

1. The combination with a ventilator including an eduction pipe, of a valve or damper for closing the pipe having a conically formed upper portion greater in diameter than the diameter of the pipe, said valve including an inverted cone shaped portion beneath and slightly smaller than the said upper portion and substantially the same diameter as the pipe, adapted to guide the valve to its seat upon said pipe. 70

2. In a ventilator, in combination, an eduction pipe having an open end, a skirt surrounding the upper end of said pipe and spaced therefrom, a series of braces connecting the skirt and the pipe and having substantially vertical inner edges near said pipe, a support above said pipe opening, a valve or damper adapted to seat upon the end of the pipe, a member to suspend the valve from said support, the described vertical edges of the braces forming guides for 80 said valve. 85

3. In a ventilator, in combination, an eduction pipe having an open upper end, a skirt encircling the same and spaced therefrom, a cap spaced above the opening of the pipe, 95 the outer marginal edge of said cap lying inside the skirt and spaced therefrom, and a ring having its inner marginal edge spaced above the outer marginal portion of the said cap, the outer marginal edge of said ring 100 being spaced from the skirt and overhanging the space between it and said pipe, a valve or damper suspended from the cap, its plane being parallel to the plane of the open end of the pipe, and normally spaced from the 105 opening and adapted to close the same, and means to guide the valve to its seat upon said opening. 110

4. In a ventilator, in combination, an eduction pipe having an open upper end, a skirt surrounding the said pipe at said upper end and extending above the opening thereof, braces connecting the skirt and pipe, a cap supported in spaced relation above said opening, a valve suspended beneath the same 115 adapted for closing the said opening but normally spaced therefrom, a ring having its inner marginal edge spaced above the marginal edge of the cap and its outer marginal edge overhanging the space between the skirt and the pipe, means for securing the ring to the cap in spaced relation and detachably secured to the braces, the said cap and ring and said valve being bodily removable from said braces. 120

5. In a ventilator, in combination, an eduction pipe, a skirt surrounding the same extending both above and below its open end, a series of braces secured to the pipe and said skirt spacing the latter from the former, 125 130

the braces constituting a series of walls forming vertical passages between the said skirt and said pipe, a cap overhanging and spaced above the pipe, and a conical ring 5 overhanging the passages spaced at its outer marginal edge from the skirt and overhanging the outer marginal edge of the said cap.

In testimony whereof I affix my signature in presence of two witnesses.

CHARLES HOFSTETTER.
